INVENTOR

UNITED STATES PATENT OFFICE

HOWARD J. MURRAY, OF BROOKLYN, NEW YORK

REMOVABLE SOCKET AND REFLECTOR

Application filed October 22, 1926. Serial No. 143,369.

My invention relates in general to a combined socket and reflector for use wherever such a device can be utilized and the invention specifically relates to a combined detachable socket and reflector for use with signalling and lighting devices as commonly found on movable vehicles.

Sockets of the type now generally known are designed so that screws or bolts and nuts are necessary to suitably mount same to the walls of the container enclosing the lighting means. When it becomes necessary to renew the lighting means the lens has to be removed. This requires tools which are not always available and in addition the removal disturbs the security of the lens as repeated removals with improper tools damage the container. Furthermore, in case of darkness it is very difficult to remove the lens even when equipped with proper tools.

Accordingly, this invention features a socket which can readily be removed from the container by the hand and without tools. The lamp then may be replaced in the usual manner, or in case of a defective socket same can be replaced by simply disconnecting the conductor.

Another object of the invention is to provide a socket of such shape that a portion of same will act as a reflector of the light from the said light source. Signalling devices as commonly found on movable vehicles depend on painted surfaces which become soiled or scratched and thereafter lose efficiency. Because of the necessity in some cases of using such signalling devices in daylight it is imperative that the reflecting surface be as efficient as possible in order to permit the use of small candle-power lamps and thus conserve the charge of the storage battery. A manually removable socket with a reflecting surface would enable such efficiency to be maintained by occasionally renewing the socket.

A still further object of the invention is to provide a renewable socket with a separate reflecting surface designed to be manually inserted with the said reflector. As such a reflector is of extremely simple design and low cost, reflecting efficiency can be easily and

cheaply maintained. It is evident that the reflecting surface may be of any suitable form and thus proper reflection of light may be effected for a given signal device, or the reflector may be varied without changing the container.

Furthermore, it is evident that in case the electrical portion becomes defective manual removal of the socket will instantly determine the cause as the socket will be removed from the body of the container.

Various other objects and advantages of the invention will in part be obvious from an inspection of the accompanying drawings and in part will be more fully set forth in the following particular description of one form of mechanism embodying my invention, and the invention also consists in certain new and novel features of construction and combination of parts hereinafter set forth and claimed.

In the drawings,

Fig. 1 is an assembly side elevation in partial section of one form of my invention to show the internal construction on the line A—A of Fig. 2.

Fig. 2 is an assembly rear view with a portion in section to show the locking arrangement.

Fig. 3 is a front assembly view showing the location of the resilient holding means and the use of the face of the socket as a reflector.

Fig. 4 is a side view of the socket showing the cut-away portion constituting the securing means.

Fig. 5 is a front view of the socket showing the reflecting surface and the slots for locking and positioning.

Fig. 6 is a front elevation of a detachable reflector arranged to be used with the socket as shown by Fig. 5.

Fig. 7 is a sectional side view of the reflector shown by Fig. 6.

Fig. 8 shows a partial vertical section of a socket having a curved reflecting surface and a locking and positioning flange.

Fig. 9 shows a partial vertical cross-section of a detachable reflector designed for use with the socket shown by Fig. 8 when 100

same is not provided with a reflecting surface.

Referring to the drawings there is shown in Fig. 1 a signal container 10 arranged to support a lens 30 securely positioned by bending over the edges 39 and the bent portion 40. The rear of the container 10 also includes a flanged portion 11 preferably drawn out from the wall so as to be of one piece and forming an opening in the shape of a tube whose sides are parallel.

Resilient means 26 are rigidly secured to the wall of the container 10 by rivets 27. The resilient means are bent so as to cause the portion 35 to project slightly outside the wall 10.

A socket composed of a casing 12, including a face 17 and an outer portion 18 is securely fastened to the container 10 by means of the projection 21 formed from the flange 11 being held against a slotted face due to the pressure of the resilient means 26 against the face 17.

Securely attached to the casing 12 is an insulating member 13 positioning and holding a spring contact 16 arranged to connect a lamp 22 to a conductor 14 held to the said conductor 16 by screw 15.

The lamp 22 is securely fastened to the casing 12 by means of the pin 36 of the lamp base pushing against the wall of the cut-away portion 38 of the said casing due to the pressure of the spring in contact 16. This arrangement is similar to that usually employed in attaching lamps to sockets.

In Fig. 2 is indicated a rear view of the assembly shown by Fig. 1. The end 16 of the resilient contact member is shown in the end of the insulating member 13. The figure also indicates the method of sliding the flanged portion 18 of the casing 12 into the flanged portion 11 of the container 10. The section also shows the cut-away portion 20 of flange 18 and the depressed portion of the flange 11.

Fig. 3 shows the front elevation of the assembly indicated by Fig. 1. The lamp 22 is shown in its relative position to the resilient means 26 pressing against the face 17 of the casing 12. The face 17 is also shown as a reflecting medium of the light from the lamp 22.

Fig. 4 shows the socket alone and indicates the form of the locking portion of the flange 18 of the casing 12. The hooked portion 37 prevents the depressed portion 21 of flange 11 (see Fig. 1) from being displaced when tension is applied to the face 17 by resilient means 26 (see Fig. 3).

Fig. 5 is a front view of the socket shown in Fig. 4 and indicates the front portion of the spring contact 25, the grooves 24 designed to permit the passage of the pin 36 into the slot 37 and finally into the locking chamber 38 (see Fig. 1). The slots 19 are cut away

in order to allow the flange 18 to be passed into the flange 12 while the depression 21 is guided into the locking surface 20 (see Fig. 4) by the said slot. The face 17 has a reflecting surface 36.

In Fig. 6 the reflecting surface 36 is separated from the socket face and becomes the reflecting disc 28 having slots 29 designed to permit the passage of the pins 36 of the lamp base of lamp 22 (see Fig. 1).

When a curved reflector base is required the flange 18 may be formed from a face 31 extending from the opposite end of the casing 12, as shown by Fig. 8. A mating detachable reflector may be formed as 32 of Fig. 9 to fit the socket of Fig. 8, and be held against same by the resilient means 26 as shown in Fig. 1.

The method of inserting the reflector and socket and of detaching same may be described as follows:

The reflectors of Figs. 6 and 9 are passed over the pins of the base of the lamp 22 which is then attached to the socket casing 12 in the usual manner. The lamp, socket and reflector are then taken in the hand and the socket is pushed into the flange 11 so that the depressed portion 21 will be passed through the slot 19 (see Fig. 4) for a distance to permit the rotation of the socket to enable the depression 21 to pass the locking hook 37. Before such a distance is negotiated the face of the reflector 28 will press against the resilient member 26 and actuate same causing a resistance to the further movement of the said reflector. The reflector will then be passed back against the face 17 and a further movement of the casing 12 will increase the resistance of the resilient members 26.

After the casing has been rotated a sufficient amount the hand is removed and the depression 21 will prevent the members 26 from ejecting the socket casing and prevent the depression 21 from passing over the hooked portion 37.

It is evident that the operation is the same without the reflector, and that the flanges will hold the socket in position axially.

It is also evident that the reflecting surface may be placed on a separate member or be a portion of the socket.

Having thus described my invention I claim:

1. In a manually detachable socket, reflector, and lamp unit designed to form a portion of a signal device, a socket providing suitable connection to an electric circuit and designed to support the said lamp in contact with such circuit, an L shaped flange forming a portion of said socket and having portions cut away designed to lock with portion of the said signal device, a reflector designed to be positioned against the face of the said socket flange, and resilient means attached to the said signal device to maintain the position

of both the said reflector and the said socket relative to the interior of the said signal device whereby the said socket, said reflector and said lamp may be removed in one manual operation.

5 2. In a signal device, means constituting a reflector consisting of a thin metal punching one side of said metal provided with a suitable reflecting substance, said reflector arranged to loosely fit a detachable signal lamp socket and to be held in a desired position by the same resilient means holding the said socket to the said signal device whereby the said socket and said reflector may be separated when removed from the action of the

10 5 said resilient means.

3. In a signal device, a manually detachable reflector one side of which is designed to suitably reflect light, said reflector designed to fit a mating flanged portion of a manually demountable electric lamp socket, resilient means for holding the said reflector against the said socket and thereby the said socket against a portion of the said signal device, and means for securing the said resilient means to the said signal device.

4. A demountable lamp socket, reflector, and lamp combination arranged to pass into or from a fitting relation with a flanged opening forming a portion of a signal enclosing container, said container equipped with resilient means designed to limit such passage in one direction and to hold the said reflector in position against the said socket and thereby the said socket against locking means forming a portion of the said container, means for connecting the said lamp to an external circuit, and means for securing the said resilient means to the said container.

40 Signed at New York city, in the county of New York and State of New York, this 21st day of October, A. D. 1926.

HOWARD J. MURRAY.
